UNITED STATES PATENT OFFICE.

CHRISTIAN OTTO, OF HASTINGS, PENNSYLVANIA.

GRAIN-SEPARATOR.

SPECIFICATION forming part of Letters Patent No. 707,251, dated August 19, 1902.

Application filed September 20, 1900. Serial No. 30,587. (No model.)

To all whom it may concern:

Be it known that I, CHRISTIAN OTTO, a citizen of the United States, residing at Hastings, in the county of Cambria and State of Pennsylvania, have invented a new and useful 5 Grain-Separator, of which the following is a specification.

The invention relates to improvements in grain-separators.

10 The object of the present invention is to improve the construction of grain-separators and to provide an exceedingly simple and inexpensive one adapted to be conveniently operated by an ordinary farmer to enable him 15 to clean rye and wheat as he requires it for sowing, milling, or for the market and capable of readily separating the cockle from the rest of the material and of conveying it out of the machine.

20 The invention consists in the construction and novel combination and arrangement of parts hereinafter fully described, illustrated in the accompanying drawings, and pointed out in the claims hereto appended.

25 In the drawings, Figure 1 is a perspective view of a grain-separator constructed in accordance with this invention. Fig. 2 is a plan view, partly in section. Fig. 3 is a detail sectional view illustrating the manner of mounting the rotary cylinder. Fig. 4 is a detail sectional view illustrating the arrangement of the trough.

Like numerals of reference designate corresponding parts in all the figures of the drawings.

35 1 designates a supporting-frame comprising a rectangular top portion 2 and sides 3 and 4, supporting the rectangular top portion and provided with bearing-recesses 5 and 6 40 for the reception of a rotary cylinder 7, which is arranged within the rectangular top portion of the supporting-frame. The sides 3 and 4, which form the supporting-legs, may be constructed in any suitable manner, and 45 the rotary cylinder is provided with exterior circular ribs 8 and 9, forming annular exterior tracks which are received by grooved rollers 9^a, mounted on the sides 3 and 4 at the bearing-recesses thereof and projecting 50 slightly above the curved bottoms of the said bearing-recesses. The grooved rollers or antifriction-wheels 9^a are arranged in suit-

able recesses, as clearly illustrated in Fig. 3 of the accompanying drawings, and the cylinder is confined in proper position on the said 55 rollers or wheels by means of curved rods 10, extending over the top of the cylinder and having their ends secured to the inner faces of the sides 3 and 4 at opposite sides of the rotary cylinder. The top portion of the frame 60 is composed of side and end bars, and one of the end bars forms a support for a hopper which is provided with a depending spout 12, extending into the cylinder at one end thereof. The hopper 11 is located above the horizontal top portion of the supporting-frame, and the cylinder is provided with an annular flange 13, extending inward and preventing the grain from escaping at that end of the machine. The spout 12 of the hopper is preferably extended through the adjacent end bar of the rectangular top portion of the supporting-frame and it delivers the grain upon the bottom of the cylinder. The cylinder is provided on its interior with indentations or 75 cavities 14, adapted to receive the small round grains of cockle which lie in the cavities or indentations and which are carried upward by the rotation of the cylinder and deposited in a longitudinal trough 14^a, located at one 80 side of the cylinder, as clearly illustrated in Fig. 2 of the accompanying drawings. The trough is provided at one end with an arm 15, which is secured to the lower face of the adjacent end bar of the supporting-frame, 85 and the other end of the trough, which is provided with a spout 16, is supported by a bracket 17, extending laterally from the trough and secured to the adjacent side bar of the horizontal portion of the supporting-frame. The spout is adapted to discharge 90 the cockle into a bag, box, or other receptacle, and the said cockle is carried along the trough to the discharge end thereof by a rotary spiral conveyer 18, located within the 95 trough and extending longitudinally thereof, as clearly shown in Fig. 2. The cleaned grain is discharged from the cylinder into an inclined chute 19, secured to the outer face of the side 3 of the supporting-frame and adapted to deliver the grain into bags or other receptacles. The cylinder is provided at one 100 end with an exterior gear consisting of a ring or band 20, provided with spur-teeth and

meshing with a pinion 21 of a longitudinal shaft 22, which is journaled in suitable bearings of the top portion of the supporting-frame. The shaft 22 is provided at one end 5 of the machine with a large pulley 24, adapted to receive a belt, and the other end of the shaft has a small grooved pulley 25 fixed to it and designed to be connected by a belt with a similar grooved pulley 27 fixed to the con-

veyer-shaft.

The separator may be driven by any suitable power, and owing to its great simplicity and cheapness it may be readily operated by the ordinary farmer and will enable him to 15 clean his grain as it is required for sowing, milling, or for the market.

It will be seen that the separator possesses great strength and durability, that it is easily operated, and that it is not liable to get out 20 of order. It will also be clear that it is effective in its operation and that it is adapted to readily separate the cockle from wheat and rye and that the small grains of cockle will be carried upward in the cavities or indentations 25 to the trough, while the grains of wheat and rye will be rejected by such indentations or cavities and will pass out of the machine at the open end of the cylinder into the inclined chute. Should any grains of rye or 30 wheat lodge endwise in the small indentations or cavities, they will drop out of the same before they reach the trough and will not be carried into the latter.

What is claimed is—

35 1. In combination with a frame, supporting-rollers mounted thereon for revolution and having annular peripheral grooves, a revoluble cylinder supported on said rollers and

having annular peripheral track-ribs engaging the grooves in the rollers, and curved rods 40 secured to the frame, arched over and bearing on the cylinder, said rods preventing the cylinder from moving from the rollers and coacting with the respectively ribbed and grooved cylinder and rollers to prevent longitudinal movement of the cylinder on the rollers, substantially as described. 45

2. The combination of a frame, supporting-rollers mounted thereon for revolution and having annular peripheral grooves, a revoluble cylinder supported on said rollers and having annular peripheral track-ribs engaging the grooves in the rollers, curved rods secured to the frame, arched over and bearing on the cylinder to prevent the latter from 55 moving from the rollers and to coact with the respectively ribbed and grooved cylinder and rollers to prevent longitudinal movement of the former on the latter, a gear 20 on said cylinder, a power-shaft 22 having its bearings on 60 said frame and provided with a pinion engaging said gear, a pulley 25 on said power-shaft, a fixed cockle-receiving trough extending longitudinally through the cylinder at one side thereof, a revoluble conveying-screw in 65 said trough, having a shaft journaled in bearings in the frame and provided with a pulley 27, and an endless belt connecting said pulleys 25, 27, substantially as described.

In testimony that I claim the foregoing as 70 my own I have hereto affixed my signature in the presence of two witnesses.

CHRISTIAN OTTO.
